UNITED STATES PATENT OFFICE.

CHARLES S. THORNE, OF TROY, NEW YORK, ASSIGNOR TO THE THORNE HOLD-FAST METAL BAR COMPANY, OF TROY, NEW YORK, A CORPORATION OF NEW YORK.

STORE-FRONT CONSTRUCTION.

1,232,869.

Specification of Letters Patent. Patented July 10, 1917.

Application filed May 20, 1915. Serial No. 29,279.

To all whom it may concern:

Be it known that I, CHARLES S. THORNE, a citizen of the United States, residing at Troy, county of Rensselaer, and State of New York, have invented certain new and useful Improvements in Store-Front Constructions, of which the following is a specification.

Reference may be had to the accompanying drawings, and the reference characters marked thereon, which form a part of this specification. Similar characters refer to similar parts in the several figures therein.

The principal object of the invention is to provide a setting for a store-front-glass, the outer member of which setting can be locked in position from the inner side of the glass.

Other objects will appear in connection with the following description.

Figure 1 of the drawings is a view in perspective, partly broken away and partly in section, of a portion of a store-front construction embodying my invention.

Fig. 2 is a view in perspective of a piece of the outer bar.

Fig. 3 is a view in perspective of a piece of the combined inner bar and base-plate.

Fig. 4 is a view in perspective of one of the anchor-blocks.

Fig. 5 is a view in perspective of one of the clamping-bolts for holding the outer bar against the glass.

Fig. 6 is a view in perspective of the nut for drawing up said clamping-bolt.

Fig. 7 is a vertical cross-section taken through the construction shown in Fig. 1 on a vertical plane between neighboring clamping-bolts.

Fig. 8 is a similar cross-section on substantially the vertical plane of one of the clamping-bolts.

Fig. 9 is a view in perspective of the lock-nut.

Referring to the drawings wherein the invention is shown in preferred form, 1 is a window-casing upon which is fixedly mounted a base-plate, 2, and an inner bar, 3, which are preferably integrally connected by means of a back-plate, 4, and gutter, 5, said back-plate being secured to a vertical part of the casing.

The inner bar, 3, is adapted to engage the inner side of a plate of glass, 6, which rests upon suitable underlying supports. 55

The glass is clamped and held between the inner bar, 3, and an outer bar, 7, which outer bar has along its outer edge an in-turned flange, 8, which underlies the outer edge of the base-plate, 2, the latter being 60 upwardly offset to receive beneath it said flange, 8.

The outer bar, 7, has along its inner edge an in-turned vertical flange, 9, which extends downward beyond the edge of the glass and 65 is provided with openings in the form of open slots 24 located at suitable intervals, adapted to receive screw-bolts, 10, the heads of which engage the outer side of the flange, 9. 70

These screw-bolts, 10, pass beneath the plate of glass and their screw-threaded inner ends are severally engaged by nuts, 12, each rotatively mounted in an anchor-block, 13, secured in fixed relation to the 75 casing by screws, 14.

The anchor-block, 13, is provided with a transverse channel, 15, which freely receives the screw-threaded portion of the screw-bolt and closely receives and fits a rectangular portion, 16, of the shank of the screw-bolt thereby preventing the screw-bolt from rotating. 80

The anchor-block is also provided with a longitudinal slot, 17, intersecting at right 85 angles the channel, 15, and adapted to freely receive the nut, 12, whereby said nut is held against longitudinal movement upon the screw-bolt while being permitted to freely rotate thereupon. 90

The nut, 12, is provided with peripheral openings, 18, adapted to receive an operating wrench or pin, whereby the nut can be rotated.

The gutter, 5, is provided with openings, 95 19, adapted to freely receive the respective nuts, 12, whereby said nuts are accessible from the inner side of the plate of glass and from within the store-window.

The plate of glass may rest upon the anchor-blocks, 13, or an interposed cushion or packing, 20, or may be supported in any other known manner. 100

A cap, 21, may be placed over each of the

nuts, 12, and secured in position by a screw, 22, inserted into the topmost opening, 18, said openings being screw-threaded for that purpose.

5 This cap, 21, thus forms a cover which excludes dirt from the opening in the gutter through which the nut projects, and also serves as a lock-nut to prevent accidental displacement of the nut, 12.

10 In setting up the construction, the combined base-plate, 2, gutter, 5, and inner bar, 3, are mounted upon the casing and the anchor-blocks, 13, are then mounted upon the base-plate at the proper intervals, and the 15 parts so mounted are secured by screws firmly to the window-casing.

The glass is then set in from the outside upon the anchor-blocks, or other supports provided for it, and in engagement with 20 the inner bar, 3, which bears against the inner side of the glass.

The screw-bolts and nuts are placed in the respective anchor-plates with the bolts projecting outwardly beneath, and somewhat 25 beyond the outer side of, the plate of glass, and the outer bar, 7, is then placed in position from the outside by sliding the slotted portions of its inner flange, 9, down over the shanks of the screw-bolts and then forcing 30 its bottom flange, 8, beneath the outer edge of the base-plate, 2, the screw-bolts being loosened sufficiently to permit this.

The screw-bolts are then drawn inward by 35 rotating the respective nuts, 18, from inside the window until the outer bar is brought into proper engagement with the outer side of the plate of glass.

If desired, the cap, 21, may be permanently riveted upon the gutter and provided 40 with a slot, 25, to afford access to the nut for operating the nut without removing the cap, the screw, 22, being removed for adjustment of the nut and replaced to lock the nut in adjusted position.

45 What I claim as new and desire to secure by Letters Patent is:

1. The combination with a window-casing; and a plate of glass; of an anchor-block in fixed relation to the casing; a channeled 50 inner bar engageable with the inner side of the glass and provided with an aperture in the bottom of its channel; an outer bar engageable with the outer side of the glass; and complementary screw-members extending 55 transversely of the glass, one rotatively mounted in said anchor-block accessible from the inner side of the glass through the aperture in the bottom of said channel, and the other connected with said outer bar, said screw-members being independent of said channeled inner bar.

2. The combination with a window-casing; and a plate of glass; of an anchor-block in fixed relation to the casing, said anchor-

block being provided with a channel angular 65 in cross-section and extending transversely of the glass, and with a slot parallel with the glass intersecting said channel on the inner side of the glass; an outer bar engageable with the outer side of the glass; a 70 screw-bolt extending longitudinally of said channel in connection with said outer bar, said bolt having an angular portion closely fitting said channel, a nut occupying said slot in the anchor-block in engagement with 75 said screw-bolt; and an inner bar engageable with the inner side of the glass and permitting access to said nut.

3. The combination with a window-casing; and a plate of glass; of a combined 80 base-plate-inner-bar-and-gutter, said gutter being provided with an opening and said inner bar being engageable with the inner side of the glass; an anchor-block mounted upon said base-plate beneath said gutter, said anchor-block being provided with a channel angular in cross-section extending transversely of the glass and with a slot intersecting said channel opposite said opening in the gutter; an outer bar engageable with 90 the outer side of the glass; means for securing said anchor-block and said combined base-plate-inner-bar-and-gutter to the casing; a screw-bolt occupying said channel in connection with said outer bar and having 95 an angular portion closely fitting said channel; and a nut occupying said slot in the anchor-block in engagement with said screw-bolt and projecting upwardly through said opening in the gutter.

4. The combination with a window-casing; and a plate of glass; of a combined 100 base-plate-inner-bar-and-gutter, said gutter being provided with an opening and said inner bar being engageable with the inner side of the glass; an anchor-block mounted upon said base-plate beneath said gutter, said anchor-block being provided with a channel angular in cross-section extending 105 transversely of the glass and with a slot intersecting said channel opposite said opening in the gutter; an outer bar engageable with the outer side of the glass, said outer bar having along its inner edge an inturned notched flange extending beyond the edge of 110 the glass, and along its outer edge an in-turned flange underlying the outer edge of said base-plate; means for securing said anchor-block and said combined base-plate-inner-bar-and-gutter to the casing; a screw-bolt 115 engaging said notched flange on the outer bar and occupying said channel and having an angular portion closely fitting therein; and a nut occupying said slot in the anchor-block in engagement with said screw-bolt and projecting upwardly through said opening in the gutter.

5. In a window-casing the combination

with a glass-engaging channeled member provided with an opening; and glass clamping screw-mechanism having a rotatory member accessible through said opening and 5 provided with a plurality of screw-threaded peripheral openings; of a cap for said opening; and a screw fitting the several periph-

eral screw-threaded openings in said screw-member in engagement with said cap, whereby said cap closes said opening and locks 10 said screw-member against rotation.

In testimony whereof, I have hereunto set my hand this 18th day of May, 1915.

CHARLES S. THORNE.
